FOLDABLE STAIRS

Reinhold B. Marschke, deceased, late of St. Paul,
Minn., by Berthold V. Marschke, administrator,
St. Paul, Minn.

Application July 31, 1946, Serial No. 687,316

6 Claims. (Cl. 228—50)

1

The present invention relates to an improvement in foldable stairs wherein it is desired to provide a low cost foldable stairway which is compactly folded and stored when not in use.

Various types of stairways have been produced for use in gaining access to attics, lofts and the like, which are not regularly used. These stairways normally fold together and are stored in the attic or loft above a pivotal closure. When desired for use the closure is usually pivoted downwardly so that the stairway may be unfolded into operable position. One of the objections to the previously produced stairways was the relatively high cost of production. In certain instances it is desirable to produce a device which will accomplish the desired result at a minimum of cost.

The object of the present invention lies in producing a foldable stairway which may be normally stored out of operable position and which may be quickly swung into operative position when desired for use. This stairway is extremely simple in design and inexpensive to manufacture. As a result this stairway serves a long felt want for a low cost simple stair construction.

A feature of the present invention lies in the fact that the stairway is pivotally connected to the stairway opening at one end of the opening while a pivoted closure is pivotally connected to the opposite end of the opening. As a result the opening closure may act as a support for the stairs until they are pivoted into operative position.

A feature of the present invention lies in the provision of a light weight stairway which is connected at its upper end by means of a flexible tape or the like to a desired point of anchor. This flexible tape is normally urged into coiled position tending to elevate the stairway. Thus the supporting tape acts as a counterweight for simplifying the stair folding operation.

A further feature of the present invention lies in the provision of hook means at the lower end of the stairway for removable engagement with the free end of the closure. As a result the opening of the closure acts to unfold the two pivoted stair sections, thereby simplifying the movement of the stairway into operative position.

These and other objects and novel features of the invention will be more clearly and fully set forth in the following specification and claims.

In the drawings forming a part of the specification:

Figure 1 is a perspective view of the stairway in readiness for operation.

FOLDABLE STAIRS

REINHOLD B. MARSCHKE, DECEASED, LATE OF ST. PAUL, MINN., BY BERTHOLD V. MARSCHKE, ADMINISTRATOR, ST. PAUL, MINN.

APPLIED JULY 31, 1946, SERIAL NO. 687,316

6 CLAIMS. (CL. 228—50)

1

Figure 2 is a sectional view through the stairway and through the aperture showing the stairway in folded condition.

Figure 3 is a perspective diagrammatic view showing the stairway in partially unfolded position.

Figure 4 is a sectional view through the floor-adjacent the stair aperture showing the spring tape in conjunction therewith.

10 The stairway A is designed to be mounted adjacent the aperture 10 in the ceiling 11 of a building or the like. The aperture 10 is similar to that often provided in the ceiling of a house or the like so as to provide an opening into the 15 attic of the building. As shown in the drawings the aperture 10 is provided with a rectangular frame 12 therein which frame is provided with substantially parallel side members 13 and 14 and substantially parallel end members 15 and 16. 20 The closure 17 is connected by aligned hinges 19 to the end 15 of the frame and is designed to close the opening within the frame 10. A latch 20 is provided at the free edge of the closure 17 for engagement with a suitable keeper 21 on the frame end 16 to hold the closure in closed position.

25 The closure 17 is preferably formed with a rectangular frame 22 having a closure panel 23 secured thereto. A cross member 24 is secured to the frame 22 at the free end of the closure. This cross member 24 is somewhat wider than the frame member so as to provide an aperture 25 between one edge of the cross member 24 and the panel 23.

30 The stairway A preferably comprises an upper stairway section 26 and a lower stairway section 27. Hinge members 29 and 30 are connected to the upper and lower sections, respectively, and are pivotally connected at 31. When the stairway is in operative position as illustrated in Figure 1 of the drawings the upper end 32 of the lower section 27 abuts the lower end 33 of the upper section 26 to strengthen the connection. Thus when the stairway is in open position the two stair sections abut and are held in abutting relation by the hinge portions 29 and 30.

35 The lower stair section 27 is formed of spaced parallel side rails 34 and 35 connected by spaced treads or rungs 40. The side rails of the two sections are similarly spaced and the treads of the two sections are properly spaced to provide a continuous stair when in the operative position shown in Figure 1.

40 55 The side rails 34 and 35 of the lower stair sec-

tion 27 are notched at their lower extremities to provide short projections 41 spaced from the remainder of the sides by notches 42. These projections 41 are designed to hook over the cross member 24 of the closure 17 when the stairway is in folded or partially folded condition. In other words, in the folded position of the stairway the cross member 24 engages in the notches 42 so as to detachably connect the lower stair section 27 to the closure 17.

As best illustrated in Figure 4 of the drawings a casing 43 is recessed into the flooring 44 of the attic or loft or other room above the ceiling 11. Within this casing 43 is provided a spring roll on which a flexible tape 45 is supported. The spring roll within the casing 43 normally tends to pull the tape 45 into the casing 43. However, the tape 45 may be pulled from the casing and held out of the casing under spring tension. The free end of the tape 45 is secured at 46 to one of the treads or rungs 40 of the upper stair section 26.

In folded position of the stairway A, the lower section 27 rests upon the closure 17. The upper section 26 is folded to overlie the lower section 27 and this upper section 26 is usually of sufficient length to rest upon the flooring 44. A cleat 47 is provided upon the floor 44 to limit the slideable movement of the ladder section 26 over the floor. The spring tape 45 tends to urge the stairway into contacting engagement with the cleat 47. When in this position the projections 41 are engaged between the cross member 24 and the panel 23 so that the cross member 24 is engaged in the notches 42.

In order to open the stair the closure 17 is swung into open position as illustrated in Figures 1 and 3 of the drawings by releasing the latch 20 from its keeper 21. This opening movement of the closure 17 tends to swing the lower stair section 27 into the position shown in Figure 3, the lower end of this section still remaining hooked to the closure.

In order to unfold the stairway into operative position the lower section 27 is raised sufficiently to disengage the cross member 24 from the notches 42. The lower end of the stairway is then free to swing into the inclined position shown in Figure 1 of the drawings, the upper end of the stairway being held against the end 16 of the frame 10 by the spring tape 45. The stairway is now in readiness for use.

In order to return the stairway to folded condition it is necessary to raise the stairway slightly, this action being assisted by the spring on the tape 45. As the latter is elevated it is pivoted into the position shown in Figure 3, with the cross member 24 engaged in the notches 42. The closure 17 is then swung into closed position, the latch 20 engaging its keeper 21 to hold the closure in closed position.

In order to hold the closure 17 in open position, there is provided a brace 50, pivotally connected at 51 to a bracket 52 to the closure frame 22. This brace slides beneath a strap 53 secured to one side of the frame 12. The upper end of the brace 50 is curved inwardly or off-set to frictionally engage the strap 53 to hold the closure open.

While this type of stairway requires a certain amount of manual manipulation to unfold into operative position and to return to folded position, the stairway sections are light weight and are counter-balanced to some extent by the spring 45. The stairway is of extremely simple con-

struction and may be added to many stair apertures previously in use.

In accordance with the patent statutes the principles of construction and operation of the foldable stairway has been described, and while the best embodiment thereof has been set forth, it is to be understood that obvious changes may be made within the scope of the following claims without departing from the spirit of the invention.

What is claimed is:

1. A stair construction for use in a stair aperture, the stair comprising in combination a closure pivotally connected to said aperture adjacent one end thereof, a stair body hinged between its ends, means slidably supporting said stair body adjacent the other end of said aperture in such a manner that the edge opposite said one end of the aperture acts as a fulcrum therefor, said stair body being slidably supported by said edge, and cooperable hook means on said stair body and on the free end of said closure for slidably connecting said stair to said closure.

2. A foldable stairway for use in a stair aperture, comprising in combination an aperture closure, means pivotally connecting said closure adjacent one end of said aperture, a ladder body including foldably connected sections, said body being slidably engageable with the other end of said aperture and hook means adjacent the lower extremity of the lowermost of said sections and cooperable means adjacent the free end of said closure engageable with said hook means to hold said lowermost section substantially parallel to said closure in engaged position therebetween.

3. A foldable stairway for use in conjunction with a stair aperture and a closure therefor, said closure being hingedly secured adjacent one end of said aperture to fold downwardly therefrom, a cross member secured adjacent the free edge of said closure, a ladder including hingedly connected sections, the upper end of said ladder being slidably engageable with the other end of said aperture and hook means adjacent the lower end of the lowermost of said sections detachably engageable with said cross member, said lowermost section held substantially parallel to said closure in engaged position thereof.

4. A foldable stairway including a stair aperture, a closure pivotally connected adjacent one end of said aperture to swing downwardly therefrom, a stair body including foldably connected sections, one of said sections being designed to lie substantially parallel to said closure, the other of said sections being slidably engageable with the other end of said aperture, detachable connecting means between said lowermost stair section and said closure, said lowermost stair section being foldable relative to the next adjacent stair section simultaneously with the pivotal movement of said closure.

5. A foldable stair construction for use in combination with flooring means provided with a stair aperture having a closure pivoted adjacent one end thereof to swing downwardly therefrom, a ladder body including a pair of foldably connected sections, means detachably connecting the lowermost of said sections to the side of said closure which is uppermost in closed position thereof and means foldably connecting said stair sections, and resilient means mounted on said flooring means and connecting with the upper of said stair sections at a locus adjacent to the side of said aperture opposite that to which said closure is pivotally connected, said last named

means supporting said upper stair section for
slidable and pivotal movement over the edge of
said opposite aperture side.

6. A foldable stair construction for use in combination with a stair aperture having a closure pivoted adjacent one end thereof to swing downwardly therefrom from one end thereof, a stair body including a pair of sections, means detachably connecting the lowermost of said sections to the surface of said closure which is uppermost in closed position thereof, means foldably connecting said stair sections, and flexible means secured to the upper section of said stair sections, and spring means mounted near the other end of the aperture and connected to said flexible means to assist in counter-balancing the weight of said stair sections, said spring means urging the upper end of the uppermost stair section toward said other end of the aperture.
